UNITED STATES PATENT OFFICE.

RAY BECKER, OF CHICAGO, ILLINOIS, ASSIGNOR TO CHAS. EMMERICH & CO., OF CHICAGO, ILLINOIS, A CORPORATION OF ILLINOIS.

DESIGN FOR A BOX.

Application filed November 12, 1924. Serial No. 11,360. Term of patent 3½ years.

To all whom it may concern:

Be it known that I, RAY BECKER, a citizen of the United States, residing at Chicago, Cook County, Illinois, have invented a new, original, and ornamental Design for a Box, of which the following is a specification, reference being had to the accompanying drawing, forming part thereof.

I claim:

The ornamental design for a box as shown.

RAY BECKER.
